UNITED STATES PATENT OFFICE.

JAMES W. PRICE, OF HENRYETTA, OKLAHOMA, ASSIGNOR TO PRICE MANUFACTURING COMPANY, OF HENRYETTA, OKLAHOMA, A CORPORATION OF OKLAHOMA.

SHADE-ROLLER.

1,247,452.

Specification of Letters Patent. Patented Nov. 20, 1917.

Application filed April 2, 1917. Serial No. 159,379.

To all whom it may concern:

Be it known that I, JAMES WALTER PRICE, a citizen of the United States, and a resident of Henryetta, in the county of Okmulgee and State of Oklahoma, have made certain new and useful Improvements in Shade-Rollers, of which the following is a specification.

One of the principal objects of my invention is to improve and simplify the construction and arrangement of parts of shade rollers of the ratchet and pawl type, and more particularly of the type in which a gravity actuated pawl is employed.

Another object of the invention contemplates the provision of a pawl and ratchet mechanism of the class described, of such nature as to be readily applicable to shade rollers of standard construction.

A further object is to provide an improved shade roller of the class described, designed with particular reference to advantages of simplicity, durability, efficiency in operation and economy in manufacture and maintenance.

With these and other advantages in view which will become apparent as the description proceeds, the invention resides in the construction, combination and arrangement of parts hereinafter more fully described and claimed, and illustrated in the accompanying drawing, in which like characters of reference indicate like parts throughout the several figures, of which—

Figure 1 represents a top plan view of a shade roller constructed according to my invention.

Fig. 2 represents an elevational view thereof, parts being shown in section to reveal the inside construction of the roller.

Fig. 3 is a perspective view of the pawl and ratchet mechanism of the roller.

Fig. 4 is a perspective view of the gravity actuated pawl.

Fig. 5 represents an end view looking at the opposite end of the roller from that at which the pawl and ratchet mechanism is positioned.

Fig. 6 is a view in section taken transversely on the plane indicated by the line 6—6 of Fig. 1 looking in the direction indicated by the arrows and showing the position of the parts when the pawl is engaged in one of the notches of the roller cap, and

Fig. 7 is a view similar to Fig. 6 showing the position of the parts when the pawl is out of engagement with the notches in the roller cap.

Referring more particularly to the drawing, the roller proper is indicated at 5, and on this roller the shade 6 is wound in the usual manner. At one end the roller is equipped with a cap 7 having a round bearing pin 8 journaled in a bracket 9, to be hereinafter more particularly described.

The opposite end of the roller has a cylindrical cap 10 mounted thereon, this cap being closed at its outer end as at 11. The end portion of the roller on which the cap 10 is mounted is centrally bored as at 12 for the reception of the rod 13, the inner end of which rotatably fits within a reduced socket 14 at the inner end of the bore. The outer end of the rod 13 projects beyond the cap through an opening punched centrally in the end 11 of the cap, and the extremity of the rod, beyond the cap, is flattened as at 15 and engages in a rectangular opening 16 formed in a bracket 17 adjacent the outer end of the latter. The rod is thus held against rotation, and the roller may revolve about the rod. The opening in the end 11 of the cap, is formed by punching the metal inwardly through the operation of suitable dies and there is thus formed around the opening an annular shoulder 18 which forms a substantial bearing, and against which the annular sleeve or collar 19 formed on the rod 13 bears.

Coiled upon this rod is a spring 20 which at its inner end is anchored on the rod as at 21. The outer end of the spring engages in an eye 22 formed at the end of a tongue which is stamped inwardly from the end 95 plate 11 of the cap 10, the end of the spring being passed through the eye and turned upon itself as clearly shown in Figs. 6 and 7. The arrangement is such that when the curtain is pulled downwardly the cap 10 which, of course, is anchored to and moves with the roller, in revolving about the rod 13, places the spring 20 under tension so that when the roller is manipulated to unlock the pawl and ratchet mechanism hereinafter described, the tension of the spring will operate to wind the curtain up on the roller.

The bracket 17 at its inner end is provided with a laterally extending portion 23

forming a base which receives the fastening device whereby the bracket may be anchored to the wall or window casing or to whatever object the roller is to be mounted on. At a point removed from its forward end the bracket is formed with an ear or tab which is bent laterally to be positioned behind the cap 10 of the roller, and then downwardly as at 25, whereby to form a frame or housing for the pawl 26. This pawl is made of one piece of material preferably, and comprises generally a flat body 27 having at its upper end a rearwardly turned portion 28 forming a counterweight, and having at its lower end a forwardly bent portion 29 which forms a tongue for engagement with the notches 30 cut at diametrically opposed points in the periphery of the cap 10 at the corner where the latter merges with its closure plate 11. The pawl, at the meeting edge of the body 27 and counterweight 28, is formed with the laterally extending pins 31 which project into horizontally aligned openings provided one in the bracket 17 and the other in the down-turned portion 25 of the ear formed on the bracket. The pawl is thus pivoted upon a horizontal axis, and the action of gravity upon the counterweight 28 serves to normally retain the tongue 29 of the pawl in engagement with the cap 10 at the outer edge or corner of the latter.

The body of the bracket 17 below the tongue or ear formed on the bracket, is stamped inwardly to provide a lug 32 which projects below the counter-weight 28 of the pawl, which serves to limit the outward movement of the tongue 29 of the pawl toward the cap 10, so that when the roller is being mounted in the brackets no inconvenience will be encountered through the pawl having swung outwardly too far. The tongue 29 of the pawl at its outer end is beveled as shown, to present an edge which is inclined to the axis of the roller, and the pawl extends in both directions beyond the corner formed at the junction of the cap 10 with its closure plate 11. Thus, although the notches 30 are relatively shallow a positive and efficient lock for holding the roller against rotation under influence of the spring, is formed when the tongue 29 of the pawl engages either of the notches. These notches are in width substantially equal to or slightly greater than the thickness of the tongue 29 of the pawl. The curtain or shade having been pulled downwardly, and being held in locked position by the pawl, and it being desired to raise the shade, the same is grasped and pulled downwardly sufficiently to rotate the cap a slight distance whereby to cause disengagement of the pawl from the notch, and then by quickly releasing the downward strain on the curtain or shade, the spring will cause the roller to rotate in a direction for winding up the shade, and the

speed of the roller will be such that the notches will pass the tongue of the pawl, before the latter, under the action of gravity can engage in the notches, so that the roller will continue to wind up the curtain until its speed is reduced by the grasp of the operator on the shade, sufficiently to allow of the pawl engaging in one of the notches. Thus the curtain or shade may be readily adjusted to any desired position and will be effectively held in that position by the operation of the pawl and ratchet mechanism. It has been found that the notches will skip the pawl, while the curtain is being wound up, even at a relatively slow speed of rotation of the roller, and this results in the fact that the curtain or shade can be very easily and smoothly adjusted. The structure is such that friction is reduced to a minimum, and this fact lends additional ease and effectiveness to the operation of the invention.

One advantage arising from the construction which I provide is that shade rollers of standard construction may be readily converted into condition for use with the bracket and pawl which I provide, by merely removing the parts of the roller excepting the rod and spring for controlling the roller, and by cutting the notches in the roller cap. No other devices of this nature with which I am familiar, present this advantage, since they all involve the use of rollers, or appurtenances thereof, of special design and construction.

The bracket 9 in which the bearing pin 8 is carried, is provided with a zigzag slot 33 in the lower branch of which the pin rests. This slot, it will be noted, presents two right angular turns at 34^a and 34 which must be followed by the pin before the latter can be taken from the bracket, and hence accidental dislodgment of the pin from the bracket will be rendered practically impossible.

On the under edge of the bracket 17 is formed an inturned leaf 35 which extends below the pawl and cooperates with the ear formed on the bracket in housing and protecting the pawl.

Although I have described the preferred embodiment of my invention, I may desire to make such changes in the construction, combination and arrangement of parts thereof, as do not depart from the spirit of the invention and the scope of the appended claims.

I claim:

1. The combination with a spring actuated shade roller, of a cap on one end of the roller having diametrically opposed notches cut in its periphery at the corner defined at its outer end, a bracket on which the roller at one end is supported, an ear formed on the bracket at the rear of the cap having a down-turned portion arranged in spaced

and parallel relation with the body of the bracket, a pawl arranged between and having pins journaled in the down-turned portion of the ear and the bracket body, said 5 pawl having a rearwardly bent portion at its upper end forming a counterweight and having a forwardly bent tongue at its lower end for coöperating with the notches in the cap in locking the roller in adjusted position.

10 2. The combination with a spring actuated shade roller, of a cap on one end of the roller having diametrically opposed notches cut in its periphery at the corner defined at its outer end, a bracket on which the roller 15 at one end is supported, a pawl pivoted on the bracket at the rear of the cap and having at its one end a rearwardly extending counterweight and at its other end a forwardly extending tongue coöperating with

the notches in the cap in retaining the roller 20 in adjusted position, said tongue having its forward edge beveled on a line inclined to the axis of the roller, said tongue extending on both sides of the corner defined at the outer end of the cap. 25

3. The combination with a spring actuated shade roller, of a cap inclosing one end of the roller and having diametrically opposed notches cut in the corner defined at its outer end, a bracket on which the roller is supported, and a gravity actuated counterweighted pawl pivotally mounted on the bracket at the rear of the cap and having a beveled tongue extending into engagement with the cap and coöperating with the 30 notches in retaining the roller in adjusted position. 35

JAMES W. PRICE.
